PROCESS OF PRODUCING IMITATION TREE BARK

William H. Burke, Superior, Wis., assignor of
one-half to Robert C. Ware, Minneapolis, Minn.

Application February 2, 1939, Serial No. 254,226

6 Claims. (Cl. 41—24)

My invention relates to improvements in an imitation tree bark or other objects having a multiplicity of surface formations and in the process of producing the same.

5 It is an object of this invention to provide an imitation tree bark for use in the production of natural appearing tree trunks, limbs, stumps, logs, rails and the like.

A further object of the invention is to provide such an object that is flexible, self sustaining, that can be spread out flat, rolled, and thus held or shaped around a frame, for instance, a tree trunk forming frame, a column, or other support.

15 Other objects of the invention will hereinafter appear.

To the above end, generally stated, the invention consists of the novel construction and the arrangement of parts and the process of producing the same.

In the accompanying drawing, which illustrates the invention, like characters indicate like parts throughout the several views.

Referring to the drawing:

25 Fig. 1 is a face view showing a sheet of the improved imitation tree bark;

Fig. 2 is a plan view of the backing having a portion of its surface covered with fillers;

Fig. 3 is a plan view of one of the facing strips;

30 Fig. 4 is a fragmentary view in section taken on the line 4—4 of Fig. 1, on an enlarged scale;

Fig. 5 is a view, on an enlarged scale, of one of the fillers in the process of being rolled;

Fig. 6 is an edge elevation of the filler shown in

35 Fig. 5;

Fig. 7 is a view of the completed fillers, bent to prevent the same from unrolling; and

Fig. 8 is a modification showing a different type of filler.

40 It is thought that this invention will be best understood by a detailed description of the different steps in the process of making the imitation tree bark, which as shown, consists of a backing or base 9 of heavy kraft paper, a plurality of fillers 10, and a facing comprising a plurality of strips of cloth 11, such as cambric or other suitable flexible material. It will of course be understood that this backing 9, may be made from cloth, wall board, or wood in sheet form 45 as a foundation.

The filler 10, shown in Figs. 5-6 and 7, is formed by rolling a sheet of paper such as news print or any other soft, absorbent of paper.

50 In Fig. 8 the filler 12 is made from a piece of hemp rope or long fibres.

The first step in the improved process is in laying the backing 9 flat on a table or other suitable support.

The second step in the process is the dipping of the fillers 10 in a liquid adhesive and in placing the same on the backing 9, in rows at odd intervals and also in bending one or more of the fillers to circular form to form the foundation for a depression or knot hole.

The adhesive in which the fillers 10 are dipped 10 of course secures said fillers to the backing 9, and when this adhesive is dry the third step in the improved process is started which consists of immersing one of the facing strips 11 in a liquid adhesive so that the same is thoroughly saturated therewith and then in spreading and stretching this strip over a section of the backing 9 and on the respective filler 10.

The fourth step in the improved process consists of shaping the facing strip 11 over the 20 fillers 10 and during this process the round fillers 10 are pinched to flatten or elongate the same to take out the regularity thereof.

The facing strip 11 is also pressed onto the backing 9 between the fillers 10 and puckered 25 and shaped to give the facing strip 11 a bark like surface. This fourth step in the process is repeated until the entire surface of the backing 9 is covered with the facing strips 11.

The adhesive with which the facing strips 11 30 are saturated, secure said strips to the backing 9 and the fillers 10 and when dry stiffens said strips so that the bark like surface is hard and the formations therein will retain their shape.

Finally the facing strips 11 are painted to represent the bark of a given tree.

The liquid adhesives heretofore referred to may be any suitable sizing that forms a suitable binder between the backing 9, fillers 10 and facing strips 11 and stiffen said facing strips so that 40 the bark like formations thereon will retain their shape.

From the above description it is evident that the complete product is capable of being rolled or shaped around a suitable form without damage 45 thereto. It is also evident that the improved product is self-sustaining and will retain its shape.

From the foregoing, it will be understood that the structures described above are capable of 50 modifications within the spirit of the invention disclosed and claimed.

What I claim is:

1. The process of producing a plurality of formations on a product consisting; first in provid- 55

- ing a backing and a pliable facing therefore; second in rolling a filler from a piece of paper and in laying the same on the backing; third in applying a sizing to the facing and in applying the facing to the backing and over the filler; and finally in shaping the facing over the filler in applying pressure to the filler to distort the same and in puckering the facing to produce formations thereon.
- 10 2. The process of producing a plurality of formations on a product consisting; first in providing a backing and a pliable facing therefore; second in rolling a filler from an absorbent sheet and in laying the same on the backing and in securing the same in place by an adhesive; third in applying a sizing to the facing and in applying the facing to the backing and over the filler; and finally in shaping the facing over the filler, in applying pressure to the filler to distort the same and in puckering the facing to produce formations thereon.
- 15 3. The process defined in claim 2 in which the filler is dipped in the adhesive.
4. The process of producing a plurality of formations on a product consisting; first in providing a backing and a fabric facing therefore; second in rolling a plurality of fillers from absorbent sheets and in bending the same to prevent the same from unrolling; third in dipping the fillers in a liquid adhesive and laying the same

on the backing; fourth in applying a sizing to the facing and in applying the facing to the backing over the fillers; and finally in shaping the facing over the fillers, and applying pressure to the fillers through the facing to distort the same and in puckering the facing to produce formations thereon.

5. The process of producing a formation on a product consisting, first, in providing a backing, a pliable filler that is relatively long and primarily substantially straight, and a pliable facing; second in laying the filler on the backing, in bending the same to give a desired formation thereto and in securing the same to the backing by an adhesive; and finally, in applying a sizing 10 to the facing and laying the facing on the backing over the filler, and thereafter in shaping the facing around the filler.

6. The process of producing a formation on a product consisting, first in providing a backing 20 and a pliable facing therefor; second in rolling a filler from a piece of paper; third in applying an adhesive to the filler, in laying the filler on the backing and in bending the same to give a desired formation thereto; and finally, in applying a sizing 25 to the facing, in laying the facing on the backing over the filler and thereafter in shaping the facing around the filler.

WILLIAM H. BURKE.
